Primary Examiner — Samantha Wood

(57) **CLAIM**

The ornamental design for a watch as shown and described.

DESCRIPTION

The file of this patent contains at least one drawing/photograph executed in color. Copies of this patent with color drawing(s)/photograph(s) will be provided by the Office upon request and payment of the necessary fee.

1. Watch

1.1 : Front

1.2 : Back

1.3 : Right

1.4 : Left

1.5 : Bottom

1.6 : Top

1.7 : Perspective

Screws shows in broken line in reproduction 1.2 form no part of the claimed design.

1 Claim, 7 Drawing Sheets
(2 of 7 Drawing Sheet(s) Filed in Color)
